UNITED STATES PATENT OFFICE.

HORACE H. CHITTENDEN, OF NEW HAVEN, CONNECTICUT, ASSIGNOR TO
FOY, HARMON & CO., OF SAME PLACE.

DESIGN FOR A CORSET.

SPECIFICATION forming part of Design No. 12,769, dated February 14, 1882.

Application filed January 16, 1882. Term of patent 3½ years.

To all whom it may concern:

Be it known that I, HORACE H. CHITTENDEN, of New Haven, in the county of New Haven and State of Connecticut, have invented a new Design for Corsets; and I do hereby declare the following, when taken in connection with the accompanying drawing and the letters of reference marked thereon, to be a full, clear, and exact description of the same, and which said drawing constitutes part of this specification, and represents a side view of the hip-section.

This invention relates to a design for a corset, with special reference to the ornamentation of the hip-section; and it consists in the ornamentation of the hip-section of the corset, as shown in the accompanying illustration, and hereinafter described.

A represents the front and B the rear parts of the corset, the intermediate space forming the hip-section. In this hip-section is a plain vertical central band, C, starting from under the arm and running downward to the lower edge. Each side of the central band, at the bottom, are gores D E. These gores are ornamented by a series of transverse ribs running

from the central band to the edge of the gores, and at substantially right angles to the central band. Each side the central band and starting from the top is the representation of a series, F G, of ribs running down nearly parallel with the central band to about the waistline, then curving respectively rearward and forward to the bottom each side of the respective gores D E, and leaving a plain space between the ribs F G and the central band and gores below.

I claim—

The herein described design for the hip-section of a corset, consisting of the representation of the plain vertical central band, C, the gores D E, representing ribs at right angles to the central band, and a series of ribs, F G, respectively to the rear and front of the central band, extending from the top of the corset downward and forward, and curving outward to the rear and front of the rib-gores, as described, and shown in the accompanying illustration.

HORACE H. CHITTENDEN.
